PORTABLE, ADJUSTABLE SOAP RACK AND TRAY

Lionel Levy, Forest Hills, N. Y.

Application August 28, 1943, Serial No. 500,347

2 Claims.

(Cl. 45—28)

This invention relates to new and useful improvements in an adjustable soap rack.

More specifically, the invention proposes the construction of an adjustable soap rack, preferably entirely constructed of plastic material, but which may be constructed of wood, glass, metal or any desired combination of these metals, and which is adjustable in a manner to support cakes of soap of different sizes and shapes to permit air to circulate completely around the outer surface of the soap to cause it to rapidly dry and prevent the formation of soap jelly, greatly increasing the life of a cake of soap while at the same time maintaining the soap in a more sanitary condition and more pleasant to use.

Still further it is proposed to characterize the soap tray by a pair of end supports having telescopic rods extended therebetween in a manner to be adjustable to receive cakes of soap of different sizes and providing a small rounded surface upon which the soap is adapted to rest with a minimum of contact between the adjacent faces of the telescopic members and cake of soap.

A further object of the invention proposes providing the end supports with downwardly extended cutouts which project beyond the bottom of the telescopic rods in a manner to permit air to enter the space between the end supports below the bottom edge of a cake of soap when rested on the rod, providing cross ventilation beneath the cake of soap.

Another object of this invention proposes the provision of a novel means for latching the telescopic rods in desired extended positions permitting the rack to be fixedly adjusted to accommodate a cake of soap of a given size.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a perspective view of a portion of a bathroom illustrating an adjustable soap rack, constructed in accordance with this invention, in position upon a portion of the bath tub.

Fig. 2 is a perspective view of the soap rack, per se.

Fig. 3 is a plan view of Fig. 2.

Fig. 4 is a vertical sectional view taken on the line 4—4 of Fig. 3.

Fig. 5 is a partial vertical sectional view taken substantially on the line 5—5 of Fig. 3.

Fig. 6 is a plan view similar to Fig. 3 but illustrating a modification of the invention.

Fig. 7 is a vertical sectional view taken substantially on the line 7—7 of Fig. 6.

Fig. 8 is a partial vertical sectional view taken on the line 8—8 of Fig. 6.

The portable adjustable soap rack and tray, according to this invention, comprises a rack 10 which is adapted to be rested on the edge of a bath tub 11 in a bathroom 12. The illustration in Fig. 1 is merely by way of example, as the tray may also be rested on a portion of a hand sink, a kitchen sink, in a soap dish attached to a wall, or directly in a soap dish built into the wall of a bathroom, kitchen, laundry, or other place.

The rack 10 is characterized by a pair of end supports 13 constructed to have cutouts 14 extended downwards from their top edges. The end supports 13 are of oval or slightly rounded shape so as to be capable of resting on a flat surface or of being inserted into a soap dish having a curved bottom.

A plurality of telescopic rods 15 are extended between the end supports 13. These telescopic rods comprise solid rods 16 extended from one of the end supports 13 and slidably engaging tubular rods 17 projecting from the other of the end supports 13. The solid rods 16 and tubular rods 17 are slidably engaged with each other permitting the rack 10 to be extended to accommodate cakes of soap of different sizes and shapes and when used as a tray it will fit in any size soap dish.

The soap rack is preferably constructed of plastic material with the rods 16 and 17 being integrally formed with their respective end supports 13. However, the soap rack may also be formed of wood, glass, metal or any desired combination of these materials and may be painted or colored to harmonize with existing patterns of bathrooms, kitchens, etc.

In Fig. 5 the bottom edge of a cake of soap resting on the soap rack is indicated by the dot and dash line AB. It will be noted that the rounded configuration of the telescopic rods 15 provide a minimum of contacting surface between the rack and cake of soap permitting the bottom to be completely dried. Furthermore, the bottom ends of the cutouts 14 extend below the bottom edge of the cake of soap, indicated by the dot and dash line AB, providing a free cross ventilation beneath the cake of soap, further insuring complete drying thereof.

In Figs. 6—8 a modification of the invention is illustrated in which a means is provided for lock-

ing the telescopic rods in a selected extended position.

In this form of the invention one of the solid rods 16' is of slightly oval shape and is provided on its top and bottom surfaces with serrations 20. Its respective tubular rod 17' is also of oval shape and is rotatively connected with its respective end support 13 by reason of having a reduced shank portion 21 rotatively extended through a complementary opening formed in its respective end support. The rotative supporting of the tubular rod 17' permits this rod to be rotated relative to the solid rod 16' into a position in which the length of the oval configuration of the tubular rod 17' will be at right angles to the oval configuration of the solid rod 16'. In this position the sides of the tubular rod 17' will rigidly grip the serrations 20 on the solid rod 16' and lock the tubular rods 15 against being extended. To free the tubular rods to be extended it is merely necessary to rotate the tubular rod 17' back to its starting position. In other respects this form of the invention is similar to that previously shown and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A soap rack and tray having end supports with telescopic rods extended between said sup-

ports, means for locking one of said telescopic rods in a fixed extended position for holding said soap rack in a desired adjusted position, said telescopic support comprising a solid section fixedly attached to one of said end supports and a tubular section slidably engaging said solid section and rotatively connected with the other of said end supports, said solid section being oval in cross-section and said tubular section being oval in cross-section and being adapted to be turned to a position in which its greatest dimension is at right angles to the greatest dimension of said solid section to frictionally grip said solid section and prevent extension of said rods forming said locking means.

2. A soap rack and tray having end supports with telescopic rods extended between said supports, means for locking one of said telescopic rods in a fixed extended position for holding said soap rack in a desired adjusted position, said telescopic support comprising a solid section fixedly attached to one of said end supports and a tubular section slidably engaging said solid section and rotatively connected with the other of said end supports, said solid section being oval in cross-section and said tubular section being oval in cross-section and being adapted to be turned so that its greatest dimension is at right angles to the greatest dimension of said solid section to frictionally grip said solid section and prevent extension of said rods forming said locking means, and serrations on opposite sides of said solid section at the ends of its greatest cross-sectional dimension for gripping the inside walls of said tubular section for assisting in the frictional gripping of said sections.

LIONEL LEVY.
